RESISTOR BULB

Gustave D. Cerf, Livingston, N. J., assignor, by
mesne assignments, to Thomas A. Edison, In-
corporated, West Orange, N. J., a corporation
of New Jersey

Application August 8, 1947, Serial No. 767,482

6 Claims. (Cl. 201—63)

1

This invention relates to structural improvements in temperature-responsive resistor bulbs.

The invention is especially concerned with an improved terminal arrangement for connecting lead-out wires to the resistance element of such a bulb.

Objects of the invention are to provide an improved electrical terminal connection which is adapted for easy installation in resistor bulbs having very small size, which is easy to assemble and is cheap and rugged in construction, and which is adapted to permit heavy tugging on the lead-out wires while providing complete strain relief on the electrical resistance element.

The invention is particularly meritorious in connection with resistor bulbs having a sensitive end adapted for direct contact with the object whose temperature is to be measured and is herein illustrated in connection with such type of bulb, but it will be understood that the invention is applicable to various types of resistor bulbs.

In the description of my invention reference is had to the accompanying drawings, of which:

Figure 1 is a view, showing the casing in section, of a resistor bulb incorporating my invention;

Figure 2 is a view of an internal unit of the bulb, with additional parts shown in dash-dot lines, taken on the line 2—2 of Figure 1;

Figure 3 is a detailed cross sectional view taken on the line 3—3 of Figure 1; and

Figure 4 is a view of one of the connecting terminals.

The resistor bulb illustrative of my invention and shown in the accompanying drawings, comprises a cylindrical core 10 made of a highly heat-conductive metal such as silver. To one end of this core there is secured, by means of a stud 11, a cylindrical insulating body 12 made of a heat-resistant material such as a suitable ceramic. This insulating body has a larger diameter than has the core and provides a shoulder at one end of the core. At the other end of the core the same has an integral peripheral flange 13 to provide it with a second shoulder. Between these shoulders there is wound on the core a coil 14 of a resistance wire having a high temperature coefficient of electrical resistance.

In resistor bulbs which are to have a sensitive contact end, a contact button 15 is preferably provided integrally with the core beyond the flange 13, and an enclosing tubular casing 16 is secured to the sensitive end of the core as to the

2

flange 13. The casing may have an internal peripheral recess 17 adapted to receive snugly the flange 13 and may be secured to the flange by turning over an edge 18 of the casing about the flange. Additionally, the casing may be welded to the flange. Preferably, the insulating body 12 has only a slightly less diameter than has the flange 13, so that it will fit closely the inside wall of the casing and hold positively the core 10 and coil 14 in spaced relation thereto.

The insulating body 12 is provided with two diametrically-opposite grooves 19 which extend lengthwise of the body. These grooves have end portions 19a of increased depth which are joined by a transverse slot 20 in the outer end of the insulating body. Also the insulating body has one peripheral groove 21. These grooves are adapted to receive two electrical connector terminals 22 of which one is shown in Figure 4. The terminals are preferably made of stainless steel so as to have high mechanical strength and low heat conductivity, the low heat conductivity being important so that the terminals will not conduct heat readily from the temperature-responsive coil and cause any substantial lag in the response of the resistor bulb. Each terminal is provided with a longitudinally-extending member 23 adapted to lie in one of the longitudinal grooves 19 and with one or more side arms 24, two being preferred as shown, which are adapted to lie in the peripheral groove 21, the shape of the terminal being thus that of a cross. Each terminal is mounted by laying it in the peripheral grooves as abovementioned with the head of the cross at the coil 14. After being so mounted, the side arms are bent downwardly to conform to the bottom of the peripheral groove and then the terminals are secured in place by winding an insulating heat-resistant thread 25 around the body in the peripheral groove, a suitable thread being one made of fiber glass. It is of course understood that the side arms of the two terminals are not long enough to touch one another but that they need extend only a short distance along the peripheral groove so as to anchor the terminals to the insulating body lengthwise of the latter to provide a positive strain relief for the electrical resistance element as will appear.

At the upper end of each terminal there is a bifurcated lug 26 initially bent outwardly as indicated in Figure 2. A lead 27 of the electrical resistance coil is bared, and coiled about this bifurcated lug as in the manner illustrated in Figure 1, after which the lug is pressed inwardly

within the longitudinal groove 19 and the wire is soldered to the terminal. The lower end of each terminal ends short of the insulating body and has two side lugs 29 bent inwardly into the groove portions 19a. The ends of lead-out wires 30 are extended into the groove portions 19a between the side lugs 29 after which the side lugs are clamped onto the leads and secured thereto as by soldering. In order to accommodate an insulation 30a on the lead-out wires there is provided a transverse groove in the outer end portion of the insulating body.

In the manufacture of resistor bulbs, it has long been a problem to find a satisfactory terminal connection for the temperature-variable resistance element, which is simple, easy to assemble, and rugged, and which enables readily the lead-out wires to be positively electrically connected to the resistor element in a manner which will provide ample strain relief for the resistor element in applications where the bulb is subjected to an extreme degree of vibration such as in aircraft applications and the like. This problem is evident by the many different terminal connections which have been heretofore proposed. Applicant has found that the present terminal connector is superior to these foregoing connectors in that it is generally simpler, easier to install and assemble and in that it enables a positive connection to be made between the lead-out wires and the resistor element which will provide the necessary degree of ruggedness and strain relief for the leads of the resistor element.

The embodiment of my invention herein shown is intended to be illustrative and not necessarily limitative of my invention since the same is subject to changes and modifications without departure from the scope of my invention, which I endeavor to express according to the following claims.

I claim:

1. A resistor bulb comprising a metal core of thermally-conductive material, a resistance element mounted on said core and having an electrical resistance variable with temperature, a casing enclosing said core and resistance element, a solid insulating piece joined to the outer end of said core and fitting closely the interior wall of said casing to hold the core and casing in spaced relation, said insulating piece being grooved at opposite sides along the length thereof and being also grooved transversely thereof, terminals lying in said lengthwise grooves and having side arms engaging said transverse grooves to anchor the terminals to the insulating piece in directions lengthwise of the latter, the inner ends of said terminals being connected to said resistance element, and means surrounding said insulating piece to hold said terminals in place.

2. A resistor bulb comprising a metal core of thermally-conductive material, a coil of resistance wire wound on said core and having an electrical resistance variable with temperature, a hollow cylindrical casing enclosing said core and coil, a solid cylindrical heat-resistant insulating body secured to the outer end of said core, said insulating body having diametrically-opposite grooves lengthwise thereof and having also a peripheral groove, two terminals lying in said lengthwise grooves and having transverse arms lying in said peripheral groove, said terminals having the ends thereof adapted for lead connec-

tions thereto and the inner ends of said terminals being connected to said coil, and heat-resistant insulating thread wound around said body within said peripheral groove to hold said terminals in place.

3. An internal unit for a resistor bulb, comprising a metal core of thermally-conductive material having a peripheral flange at one end, a heat-resistant insulating body secured to the other ends of said core and having substantially greater dimensions in cross section than has said core, said insulating body having grooves lengthwise thereof and a transverse peripheral groove intersecting said lengthwise grooves, said lengthwise grooves having portions of increased depth at the outer end of said body, and terminals mounted in said lengthwise grooves, each of said terminals having a cross arm engaging said peripheral groove and having inwardly-projecting lead-connecting lugs at their outer ends disposed in said groove portions of increased depth.

4. An internal unit for a resistor bulb, comprising a metal core of thermally-conductive material, a heat-resistant insulating body secured to one end of said core and having a substantially greater cross sectional area than has the latter, said insulating body having grooves therein along the length thereof and having a peripheral groove intersecting said lengthwise grooves, terminals in said lengthwise grooves having side extensions engaging said peripheral groove, said terminals being adapted at the ends for lead connections thereto, and heat-resistant insulating thread wound in said peripheral groove to hold said terminals in place.

5. In a resistor bulb having a tubular casing: an internal resistor unit comprising a metal core of thermally-conductive material having an integral peripheral flange at one end, a cylindrical insulating body of heat-resistant material joined to the other end of said core, a coil of temperature-responsive wire wound on said core in the space between said flange and said insulating body, said body having diametrically-opposite grooves therein throughout the length thereof and having a peripheral groove, terminals in said lengthwise grooves joined at the inner ends thereof to said coil, said terminals having side arms lying in said peripheral groove, and a thread of insulating heat-resistant material wound about said insulating body within said peripheral groove to hold said terminals in place.

6. The resistor bulb set forth in claim 5, wherein in each of said terminals has two side arms giving the terminal the shape of a cross, both of said side arms lying within said peripheral groove and having an overall length less than half the circumferential length of the peripheral groove.
